CLAIM

The ornamental design for a cooling pack, as shown and described.

DESCRIPTION

FIG. 1 is a perspective view of a cooling pack showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof;

FIG. 8 is a front perspective view, showing the cooling pack in an alternate wrapped position; and,

FIG. 9 is a rear perspective view thereof.

The broken line showing of a person is included for the purpose of illustrating environmental structure and forms no part of the claimed design.
